CLAIM

The ornamental design for a roll-up bag, as shown and described.

DESCRIPTION

FIG. 1 is an isometric view of a roll-up bag showing our new design.

FIG. 2 is a front view thereof.

FIG. 3 is a back view thereof.

FIG. 4 is a top view thereof.

FIG. 5 is a bottom view thereof.

FIG. 6 is a left side view thereof.

FIG. 7 is a right side view thereof; and,

FIG. 8 is an exploded view thereof.

The broken lines shown in the Figures show portions of the roll-up bag that form no part of the claimed design. The shade lines in the Figures show contour and do not claim surface ornamentation or treatment.
